SCRAPING AND LEVELING MACHINE

Charles E. Moody, Visalia, Calif.; Arthur J. Moody
administrator of said Charles E. Moody, deceased

Application March 15, 1946, Serial No. 654,712

2 Claims. (Cl. 37—180)

1

This invention relates to earth levelling devices and more particularly to a scraping and grading machine for levelling and grading land.

A main object of the invention is to provide a novel and improved earth levelling machine of very simple construction, which is easy to operate and which is very dependable in performance.

A further object of the invention is to provide an improved land grading device having tractable support means of substantial bearing area adapted to maintain the scraping element of the device in a substantially horizontal position under a wide range of conditions of terrain, said device being further provided with means affording a relatively small turning radius for the device when it is desired to reverse the direction of operation of the grading machine.

Further objects and advantages of the invention will become apparent from the following description and claims, and from the accompanying drawing, wherein:

Figure 1 is a side elevational view of a land grading machine constructed in accordance with the present invention.

Figure 2 is a bottom plan view of the grading machine of Figure 1.

Figure 3 is a cross-sectional view taken on line 3—3 of Figure 1.

Figure 4 is a cross-sectional view taken on line 4—4 of Figure 1.

Figure 5 is a cross-sectional detail view taken on line 5—5 of Figure 4.

Referring to the drawing, 11 designates the frame of the grading device, said frame being generally rectangular in plan and being of substantial length, and including spaced side members each comprising a lower member 40, an upper member 41, and an intermediate member 42. Frame 11 is supported at its front end by a longitudinally serrated roller member 12 extending substantially for the full width of frame 11 and journalled in the rearwardly extending legs 13, 13 of a U-shaped roller-supporting member 14 which has its bight pivotally secured to the front cross-bar 15 of frame 11 at its center by a vertical king pin 16 to permit relative rotation of member 14 with respect to frame 11 in a horizontal plane about a vertical axis, the cross bar 15 being connected at its ends to the intermediate members 42. Frame 11 is supported at its rear end by a longitudinally serrated roller member 17 also extending substantially for the full width of the frame and journalled in the rearwardly extending legs 18, 18 of a

2

U-shaped roller-supporting member 19 which has its bight pivotally secured to the rear cross-bar 20 of frame 11 at its center by a vertical king pin 21 to permit relative rotation of member 19 with respect to frame 11 in a horizontal plane about a vertical axis, the cross bar 20 being connected at its ends to the intermediate members 42. It is to be noted that the U-shaped support member 14 with its bight pivotally connected to the cross bar 15 with its legs having the roller 12 journalled therein and the U-shaped support member 19 with its bight pivotally secured to the cross bar 20 with its legs having the roller 17 journalled therein provide a castering action for the frame 11. Support member 14 is linked to support member 19 by a pair of cables 22, 22, each cable being connected to one of the arms 13 and extending across the forward portion of an opposite side of frame 11 over a pulley 23 journalled on a side bar of the frame and over a second pulley 24 journalled on said side bar to the end of rear support member 19 adjacent said side bar. Therefore, cables 22 cross each other and when front roller 12 is turned on its king pin 16 in one direction with respect to frame 11 rear roller 17 is turned in the opposite direction, thereby providing a shortened turning radius for the device.

The forward end of frame 11 is connected by cables 25, 25 to a suitable mobile draft vehicle such as a tractor. When the tractor turns, the drag exerted on the front roller 12 causes such roller to turn automatically in the proper direction on its king pin 16. The rearwardly located position of the roller 12 relative to the king pin 16 assists this automatic turning but is not entirely essential.

Pivotally connected to the side bars of frame 11 by horizontally disposed pivots located at the intermediate portion of frame 11 is a U-shaped scraper blade member 26, the bight portion comprising a vertical transverse blade portion and being formed with a rearwardly projecting threaded lug member 27 at the center portion 45 thereof adjacent its upper edge. Lug 27 is threadedly engaged by a vertical adjusting shaft 28 which extends through an upper cross-bar 29 secured to frame 11 and is journalled in a bearing member 30 pivotally supported in a pair of angle brackets 31, 31 mounted on each side of shaft 28 on cross-bar 29. Secured to the upper end of shaft 28 is a crank member 32 which bears on top surface of bearing member 30, providing a thrust bearing for shaft 28. By 50 manually rotating crank member 32 the eleva-

tion of the vertical transverse blade portion of U-shaped scraper blade member 26 may be adjusted as desired by the operator.

The device is employed to grade and smooth land to place it in a suitable level condition, as for example, for irrigation. The large front and rear rollers provide a large bearing surface for the frame 11 and prevent the frame from tilting sideways in soft dirt or muddy ground during the grading operations, thereby insuring accurately horizontal scraping by blade member 26. During straight forward movement of the device the linkage cables 22, 22 maintain the rollers 12 and 17 in parallel relationship. When the device is being turned, as when the direction of operation is to be reversed, the linkage cables cause the rollers to turn in opposite directions with respect to frame 11, thereby greatly shortening the turning radius of the device and saving time and reducing fuel consumption by the tractor.

While a specific embodiment of a land levelling machine has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. In a scraping and levelling machine including a scraper blade, a frame having spaced side members each comprising a lower member, an upper member, and an intermediate member, a cross bar arranged transversely of said side members adjacent the forward and rearward ends thereof and connected at its ends to said intermediate member, a U-shaped member positioned underneath said frame adjacent each of said cross bars and having the bight pivotally connected to the adjacent cross bar for movement about a vertical axis with its legs extending rearwardly of said axis and a roller journaled in the legs of each of said U-shaped members whereby there is provided a castering action for said frame, guide means positioned adjacent to and carried by the lower member of each of said side members intermediate its ends, a first flexible cable having its intermediate portion in engagement with the guide means on one of said lower members and having one end connected to one of the legs of the U-shaped member pivotally connected to the rearward cross bar and having the other end connected to the diagonally opposite one leg of the U-shaped member pivotally connected to the forward cross bar, and a second flexible cable having its intermediate portion in engagement with the guide means on the other of said lower members and having one end connected to the other of the legs of the U-shaped member pivotally connected to the rearward cross bar and having the other end connected to the diagonally opposite other leg of the U-shaped member pivotally connected to the for-

ward cross bar, whereby movement of the rearward U-shaped member in one direction causes simultaneous movement of the forward U-shaped member in the opposite direction.

- 5 2. In a scraping and levelling machine including a scraper blade, a frame having spaced side members each comprising a lower member, an upper member, and an intermediate member, a cross bar arranged transversely of said side members adjacent the forward and rearward ends thereof and connected at its ends to said intermediate member, a U-shaped member positioned underneath said frame adjacent each of said cross bars and having the bight pivotally connected to the adjacent cross bar for movement about a vertical axis with its legs extending rearwardly of said axis and a roller journaled in the legs of each of said U-shaped members whereby there is provided a castering action for said frame, guide means embodying spaced vertically disposed rotatable pulleys positioned adjacent to and carried by the lower member of each of said side members intermediate its ends, a first flexible cable having its intermediate portion in engagement with the pulleys on one of said lower members and having one end connected to one of the legs of the U-shaped member pivotally connected to the rearward cross bar and having the other end connected to the diagonally opposite one leg of the U-shaped member pivotally connected to the forward cross bar, and a second flexible cable having its intermediate portion in engagement with the pulleys on the other of said lower members and having one end connected to the other of the legs of the U-shaped member pivotally connected to the rearward cross bar and having the other end connected to the diagonally opposite other leg of the U-shaped member pivotally connected to the forward cross bar, whereby movement of the rearward U-shaped member in one direction causes simultaneous movement of the forward U-shaped member in the opposite direction.
